UNITED STATES PATENT OFFICE.

WILLIAM N. MANUEL, OF CORNING, NEW YORK, ASSIGNOR TO CORNING GLASS WORKS, OF CORNING, NEW YORK, A CORPORATION OF NEW YORK.

DESIGN FOR A LAMP COVER GLASS.

Application filed April 7, 1923. Serial No. 5,722. Term of patent 14 years.

To all whom it may concern:

Be it known that I, WILLIAM N. MANUEL, a citizen of the United States, residing at Corning, in the county of Steuben and State of New York, have invented a new, original, and ornamental Design for a Lamp Cover Glass, of which the following is a specification, reference being had to the accompanying drawings, forming part thereof, in which:—

Figure 1 is a rear view of a lamp cover glass, showing my new design, and

Fig. 2 is a section taken on the line 2—2 of Fig. 1.

I claim:

The ornamental design for a lamp cover glass, as shown.

WILLIAM N. MANUEL.
